E. A. STEPHENS.
CONCRETE SASH WEIGHT.
APPLICATION FILED MAR. 16, 1920.

Patented Aug. 2, 1921.

UNITED STATES PATENT OFFICE.

EDWARD A. STEPHENS, OF LOS ANGELES, CALIFORNIA.

CONCRETE SASH-WEIGHT.

1,386,538.

Specification of Letters Patent.

Patented Aug. 2, 1921.

Application filed March 16, 1920. Serial No. 366,348.

To all whom it may concern:

Be it known that I, EDWARD A. STEPHENS, a citizen of the United States, residing at Los Angeles, in the county of Los Angeles and State of California, have invented new and useful Improvements in Concrete Sash-Weights, of which the following is a specification.

This invention relates to building hardware and particularly to sash-weights and has for its object to provide an improved sash-weight the body of which may be made of cement to provide an inexpensive construction and a further object is to provide for the attachment of a pulley and its bearing to the concrete blocks. A further object is to provide for the attachment of additional sections or pieces of cement blocks to enable the desired counterbalance, all with a minimum expense of time and labor and material and by the use of material of inexpensive character. The invention consists of the construction, the combination, and in details and arrangements of the parts, embodiments of which invention are illustrated in the accompanying drawings and described and claimed hereinafter.

Figure 1 is a side elevation of a single block weight with the attached pulley.

Fig. 2 is a cross-section on line 2—2 of Fig. 1.

Fig. 3 is a plan view of a modified form of the block having added sections.

Fig. 4 is a front elevation of the construction in Fig. 3.

Fig. 5 is a section on line 5—5 of Fig. 3.

Fig. 6 is a section on line 6—6 of Fig. 4.

The improved weight comprises a main cement block 2 of any suitable proportions and has in its upper end a pulley pocket 3 extending medially between the front and back faces of the block and transversely extending from these faces is a pair of apertures or recesses 4—4 in alignment with each other the parallel side walls of which form guides between which there may be disposed a transversely extending bearing part in the form of an inverted U to straddle over an inserted pulley 5 having projecting spindles 5' on each side to bear in the out turned arms 6' of the bearing member 6. This member may be made of stamped sheet metal or otherwise and is loosely dropped into the pockets 4—4 in transverse position.

The bearing member 6 is secured in the

inserted position as by means of a fastening wire 7 passed over the upper part of the member 6 which may be transversely grooved as at 6a to form a seat 4 for the fastening wire, the ends of which are passed down over the front and back faces of the block 2. These faces are provided with grooves 8 in which the wire 7 lies and the ends are bent under the bottom end of the block and twisted together as at 9 to form a secure fastening holding the bearing member 6 in place on the spindles 5'. Space is provided around the pulley 5 for the insertion and running of the usual sash cord C. The axial shifting of the pulley with its bearing 6 is prevented by the portions of the fastening wire 7 that engage the outer corners of the bearing parts 6' these corners being shown as turned down and arranged about in the planes of the front and back faces of the block 2.

Additional weight sections may be added at either end of the block as shown in Figs. 3 to 6 inclusive and upper end blocks of U-shape and plan are shown at 2a and 2b. The upper end of the block 2 is shown in Figs. 4 and 5 as provided with longitudinal recesses or grooves 11 and the lower faces of each of the blocks 2a and 2b are provided with tongues or beads 12 so that the block sections are interlocked with their bottom faces in butted relation and are prevented from turning when superposed. The top blocks 2a and 2b provide a clearance space or chamber through which the sash cord C may pass and the upper face of each block 2a and 2b is provided with a transverse groove 13 along which the top portion of the fastening wire 7, Figs. 5 and 6, extends when it is applied to tie the block section together. The backs of these additional sections are also grooved at 14 to receive the wire and prevent the sections from shifting end-wise.

Bottom sections 2c and 2d may also be added to the main block 2 and the several sections interlocked by longitudinally extending interlock grooves and beads 15 and 16 respectively and the bottom block sections are also grooved in their front and back faces at 17 to receive the wire 7.

From the above it will be seen that the sash-weight can be readily varied to secure the effective counterbalancing property by the addition of upper and lower sections as

may be desired and the whole can be secured by a single fastening wire such as shown at 7.

Various changes may be made without departing from the spirit of my invention as claimed.

What is claimed is:

1. A sash-weight comprising, in combination, a cement block with a pulley wheel pocket in one end; a detachable bearing member adapted to be arranged across the pocket; a pulley wheel disposed in the pocket and having running engagement with the bearing member; and a fastening device 15 for holding the bearing member in place; the block having in its pulley end a pocket to receive the bearing member; the pocket for the bearing member being substantially the same in depth as the height of the bearing member so that the block can be moved to the upper limit without interference of the bearing member or its wheel.
2. A sash weight comprising a cement block provided at its upper end with a recess and a pocket extending downwardly from said recess, a detachable bearing member positioned in said pocket over said recess, a pulley journaled in said bearing and projecting downwardly into said pocket and 30 a fastening device extending lengthwise around the cement block and over said bearing member for securing the latter to said block.
3. A sash-weight comprising, in combination, a cement block with a pulley wheel pocket in one end; a detachable bearing member adapted to be arranged across the pocket; a pulley wheel disposed in the pocket and having running engagement with 35 the bearing member; and a fastening device for holding the bearing member in place; the block consisting of interlocking sections all secured together by the same fastening means.
- 45 4. A sash weight comprising an elongated member formed of detachably connected cement blocks, one of which is provided in its upper portion with a pocket, a bearing member arranged within said pocket, a pulley ar-

ranged in said pocket and journaled on said bearing member and a tie passing lengthwise around the body of the weight for retaining the sections thereof in assembled relation.

5. A sash weight comprising a main weight member with a pulley pocket in its upper end, a detachable bearing member adapted to be arranged over the pocket, said member consisting of an inverted U-shaped guard having laterally extending portions forming half bearings, oppositely disposed recesses in the side walls of the pocket to receive the laterally extending bearing portions, said recesses having a depth equal to the height of the guard member, a pulley wheel having trunnions disposed in the pocket, said trunnions having a bearing in the side walls of the pocket and retained therein by the lateral half bearings on the guard member, and fastening means extending around the main member to retain the guard and pulley in place.

6. A sash-weight comprising a main weight member with a pulley pocket in its upper end, a detachable bearing member adapted to be arranged over the pocket, said member consisting of an inverted U-shaped guard having laterally extending portions forming half bearings, oppositely disposed recesses in the side walls of the pocket to receive the laterally extending bearing portions, said recesses having a depth equal to the height of the guard member, a pulley wheel having trunnions disposed in the pocket, said trunnions having a bearing in the side walls of the pocket and retained therein by the lateral half bearings on the guard member, and fastening means extending around the main member to retain that guard and pulley in place, and sections adapted to be added to the main member to increase the weight thereof, said sections having interlocking means to prevent their lateral displacement.

In testimony whereof I have signed my name to this specification.

EDWARD A. STEPHENS
